UNITED STATES PATENT OFFICE.

ROBERT H. HASSSLER, OF INDIANAPOLIS, INDIANA.

TRUSSSED FRAME FOR VEHICLES.

1,266,938.

Specification of Letters Patent. Patented May 21, 1918.

Application filed November 6, 1916. Serial No. 129,860.

To all whom it may concern:

Be it known that I, ROBERT H. HASSSLER, a citizen of the United States, residing at Indianapolis, in the county of Marion and State of Indiana, have invented certain new and useful Improvements in Trussed Frames for Vehicles, of which the following is a specification.

The object of this invention is to strengthen and stiffen the body-panels of automobiles where they are weakened by the usual door openings, to utilize the splash-plate as a part of this accomplishment and in connection therewith make the splash-plate more durable for all purposes and neater in appearance, and to combine the running-board, body-sill and frame with the splash-plate to form a trussed extension of the frame which will support the body-panel directly under the door openings.

I accomplish the above, and other objects which will hereinafter appear, by the mechanism illustrated in the accompanying drawings, in which—

Figure 1 is a view in side elevation of an automobile embodying my invention. Fig. 2 is a top plan view of same. Fig. 3 is a vertical section on an enlarged scale, on the line 3—3 of Fig. 2 and Fig. 4 is a like section on the line 4—4 of Fig. 2.

Like characters of reference indicate like parts in the several views.

While I have shown my invention in connection with a car having a single side door, it is even more applicable to cars with two door openings on a side, because the body panel is thereby additionally weakened.

Referring to the drawings, the body-panel 5 is of sheet metal, and of usual construction. Its lower edge is bent in and nailed or otherwise fastened to the body-sill 6, usually of wood, which sill supports a floor 7. The body-panel is bowed or curved outwardly, in the manner shown in Fig. 2.

The sill 6 is supported by the channel bars of the main frame 8. These channel bars are usually parallel with each other as shown in Fig. 2, and for a major portion of the length of the body are considerably inside of the curved body lines, with the result that the wooden sills and sheet metal panels are overhanging and unsupported by the frame 8 where the door openings are

cut through. This causes vibration, and frequent cramping and buckling of the side panels at the doors. This I overcome by forming a support out of the splash-plate 9, which extends vertically from the body-sill 6 to the running-board 10, and has its upper and lower edges bent at right angles to form flanges 12 and 13 which are nailed or otherwise fastened to both of said members 6 and 10. The splash-plate is of sheet metal, bent longitudinally to conform with the said bowed shape of the body-panels. The inner edge of the running-board 10 is curved in like manner to conform with the bowed shape of the adjacent body-panel.

The running-board 10 is supported from the main frame 8, by means of a plurality of hangers 14, having ears at their upper ends through which fastening rivets are passed into the frame. The lower ends of the hangers are bent out horizontally to receive the superimposed running-board which is rigidly secured by bolts, as shown. The hangers 14 serve as the braces or struts of a truss comprising a straight frame member 8 and body sill 6, splash-plate 9 and running-board 10, all concaved with relation to the straight member 8.

It will be noted that the greatest strength of the splash-plate 9, is disposed under the body-sill 6, to support said sill, and that the splash-plate is held absolutely to its given shape by its flanges 12 and 13 fastened to the body-sill and running-board. It will also be noted that the upper edge of the vertically straight body-portion of the splash-plate 9 is rigidly connected with the frame 8, by being riveted directly thereto at its front end, as shown in Fig. 3, and by means of the body-sill 6, floor 7 and a block 11, as shown in Fig. 4, at other places.

This provides a stiff and strong truss construction at each strut 14, and, with the vertically straight splash-plate which is bowed longitudinally, together with the correspondingly curved body-sill and running board, the truss principle is additionally applied to the support of the body-panel where the door openings weaken it.

The lower flange 13, of the splash-plate 9, supports the front fender 16, to which it is riveted from where the latter curves up from the front end of the running board.

Having thus fully described the preferred form of my invention as at present advised,

what I claim as new and wish to secure by Letters Patent of the United States, is—

1. The combination with a body-panel, a sill to which the panel is fastened, and a frame member supporting the sill, of a running-board below the body-panel, diagonal strut-hangers from the frame to the running-board, a longitudinally curved and vertically straight splash-plate connecting the running-board with the sill, and rigid connecting means between the upper edge of the splash-plate and the frame-member.
2. The combination with a body-panel, a sill to which the panel is fastened, and a frame member supporting the sill, of a running-board below the body-panel, strut-hangers from the frame to the running-board, a longitudinally curved and vertically straight splash-plate connecting the running-board with the sill, an end of said splash-plate being rigidly fastened to said frame member, and other portions of the splash-plate being connected with the said frame member by rigid connecting means.
3. The combination with a curved body panel having a door opening, a sill curved to conform with the curvature of the panel to which sill the panel is fastened, and a

frame-member under and supporting the sill, of a running-board below the body-panel, diagonal strut-hangers from the frame to the running-board, and a vertical splash-plate from the running-board to the sill curved longitudinally with the body-panel.

4. The combination with a curved panel having a door opening, a sill curved to conform with the curvature of the panel to which sill the panel is fastened, and a frame member under and supporting the sill, of a running board below the body-panel having its inner edge curved with the body panel, strut-hangers fastened to the frame and supporting the running-board to which they are fastened, a vertical splash-plate from the running-board to the sill curved longitudinally with the body-panel, and flanges at the top and bottom of the splash-plate substantially at right angles to the latter, through which the plate is fastened to the sill and running-board.

In witness whereof, I have hereunto set my hand and seal at Indianapolis, Indiana, this 24th day of Oct., A. D. one thousand nine hundred and sixteen.

ROBERT H. HASSSLER. [L.S.]
